FIG. 1 is a front, left isometric view of a base for water flosser.
FIG. 2 is a rear perspective view of the base of FIG. 1.

FIG. 3 is a front elevation view of the base of FIG. 1.

FIG. 4 is a rear elevation view of the base of FIG. 1.

FIG. 5 is a right side elevation view of the base of FIG. 1.

FIG. 6 is a left side elevation view of the base of FIG. 1.

FIG. 7 is a top plan view of the base of FIG. 1; and,

FIG. 8 is a bottom plan view of the base of FIG. 1.

The broken line showing of a reservoir and areas immediately
adjacent to the shaded areas represents boundaries to the
claimed design with the broken line itself and all lines within
forming no part of the claimed design.**1 Claim, 8 Drawing Sheets**
